UNITED STATES PATENT OFFICE.

PHILIPP KENEDER, OF MUNICH, GERMANY, ASSIGNOR TO EUGEN ZENTZ, OF MUNICH, GERMANY.

MACHINE FOR ABRADING AND POLISHING FLOORS.

1,121,373.

Specification of Letters Patent.

Patented Dec. 15, 1914.

Application filed September 9, 1914. Serial No. 860,839.

To all whom it may concern:

Be it known that I, PHILIPP KENEDER, a citizen of Germany, residing at Munich, Bavaria, Germany, have invented certain new and useful Improvements in Machines for Abrading and Polishing Floors; and I do hereby declare the following to be a full, clear, and exact description of the invention, such as will enable others skilled in the art to which it appertains to make and use the same.

This invention relates to a machine for abrading and polishing floors after previous application of wax, so that no hand labor is necessary except that required in guiding the machine which consists of a frame carrying a suitable electric motor, a sliding guide for the chip holder, a pulley with a hub for the polishing brush, which is arranged on a vertically rotary axis and devices to tension the driving belts of the chip holder and the polishing brush.

The invention consists in the combination and arrangement of the parts of the machine as hereinafter described and shown in the accompanying drawings and specifically pointed out in the claims.

In the drawings, Figure 1 is a side view of the machine, Fig. 2 a bottom plan view. Fig. 3 is a transverse section on the line A—B of Fig. 2. Fig. 4 is a front view with the polishing brush in operative position.

The machine consists of a metal tube frame *a* which is pushed over the floor by means of the wheels *b* and the driving handle *g*. The electric motor *d*, with the controller *e* and the switch *f* is arranged on the bridge piece *i*.

The chip holder *m* and the rotary polishing brush *l* are placed on the under side of the frame *a* near the front end and may be removed and replaced one by the other.

For the reception of the chip holder *m* the frame *a* is provided with a sliding guide *n* which is arranged on the longitudinal shanks of the frame. The rotary polishing brush *l* is either fixed on the hub of a pulley *v* and with this arranged on a vertically rotary axis which is directly driven, or loosely set up on this axis and especially driven. In both cases the motion is effected by wedge formed driving belts and pulleys from the axis *k* of the electric motor *d*.

In the drawings the axis *k* is provided with a double pulley *o*, the driving belt *p*

is led to a pulley *r* arranged near the rearward end of the frame *a* at the cross head *q*. The pulley *r* bears a crank-pin *s* and forms therefor a crank-disk which revolves slower than the pulley *o*. On the crank-pin *s* is fixed the crank-rod *t* which is detachably connected with the chip holder *m*. From the pulley *o* a second driving belt *u* is led to a pulley *v* arranged near the forward end of the frame on a vertical axis 60 which bears in the cross head *q*. The pulley *v* is nearly of the same diameter as the pulley *o* and lies between the brackets of the sliding guide *n*. The rotary brush-disk *l* is detachably attached to the hub of the 70 pulley *v* for instance by means of nuts or by bayonet-lock and key, as represented in the drawings.

To tension the driving belts *p* and *u*, the cross heads *q*, *q*¹ may be slidably arranged 75 on the frame *a* and the sliding guide *n* and provided with convenient span-devices. Such a span-device is shown in the drawings and consists of a screw bolt *w* at each end of the frame *a* and of a nut *x* in form of a 80 sleeve which is rotatable in the frame *a* and may be turned by a squared stake-key. By revolving the sleeve-nut *x* in one direction or the other the bridge pieces *q*, *q*¹ are moved away from or caused to approach the cross 85 parts of the frame *a* and thereby the belts *p* and *u* loosened or tensioned.

If the machine is used to abrade the floor the chip holder *m* is in action and the rotary brush *l* removed. The electric motor 90 *d* moves the chip holder *m* back and forth by means of the crank-rod *t* whereby the floor is abraded in the direction of the planks. The rotation of the pulley *r* is much slower than that of the pulley *o* and 95 therefore the chip holder *m* is slowly reciprocated, a great advantage for the abrading work.

If the machine is used to polish the floor after waxing, the chip holder *m* and the 100 crank rod *t* must be removed and the rotary brush inserted. The latter is rotated at a very high speed, its rate of revolution being nearly the same as that of the motor axis *k*, whereby the polishing is done in a perfect 105 manner.

During the abrading work the pulley *v* runs loosely, while during the polishing work the pulley *r* runs loosely.

Having described my invention, what I 110

claim as new and desire to secure by Letters Patent, is:

1. In a floor-surfacing machine, the combination of a frame, cross heads slidably carried near opposite ends thereof, tool holders supported from said frame, a motor carried by said frame, pulleys carried by said cross heads, connections from said motor to said pulleys for driving the latter, 5 connections from said pulleys respectively to said tool holders, whereby one of the latter may be reciprocated and the other thereof rotated, and means for moving said cross heads on said frame to vary the tension of 10 the connections from the motor to the pulleys.
2. In a floor-surfacing machine, the combination of a frame, cross heads slidably

carried near opposite ends thereof, a pulley carried by each cross head, a motor carried 20 by said frame, belts connecting the shaft of the motor with said pulleys, means for moving said cross heads on said frame to vary the tension of said belts, a tool holder supported by one of said pulleys and rotatable therewith, a second tool holder supported from said frame, and a crank connection from the upper pulley to said second tool holder whereby the latter is adapted to be reciprocated. 25

In testimony whereof I hereunto affix my signature in the presence of two witnesses.

PHILIPP KENEDER.
